UNITED STATES PATENT OFFICE

JAMES H. McDERMINT, OF EAST CLEVELAND, OHIO, ASSIGNOR TO THE SWARTWOUT COMPANY, OF CLEVELAND, OHIO, A CORPORATION OF OHIO

VENTILATOR

Application filed March 27, 1929. Serial No. 350,187.

This invention relates to improvements in ventilators and particularly that type of ventilators having a revolving cowl which may be closed by pivoted louvers operated by 5 a flexible member from a point far removed from the cowl.

It is the object of the invention to provide a catch mechanism for holding the louvers in various positions of adjustment, which is 10 simple in construction and sure in operation.

A further object is to provide louvers which interfit when shut to effectively close the ventilator, and also to provide the louvers with a hinge construction which is inexpensive to 15 manufacture yet which will permit easy operation of the louvers at all times.

A still further object is to provide a thrust bearing for the rotary cowl which prevents binding of the cowl on its base when subjected 20 to extreme weather conditions.

With these and other objects in view the invention resides in all the novel features of construction and combination of parts herein disclosed and particularly pointed out 25 in the appended claims.

In the drawings, Fig. 1 is a central vertical section through the improved ventilator with the latch mechanism for the pivoted louvers in side elevation; Fig. 2 is a fragmentary 30 tail sectional view of the louvers in closed position; Fig. 3 is an enlarged vertical section through the bearing assembly of the cowl; Fig. 4 is a bottom plan view of the lower bearing; Fig. 5 is an enlarged detail 35 sectional view on the line 5—5 of Fig. 1; Fig. 6 is a sectional view on the line 6—6 of Fig. 5; Fig. 7 is an enlarged vertical section through the latch mechanism showing in full lines the position of parts when the louvers are held 40 in open position, and in dotted lines the position of the parts when the louvers are closed; Fig. 8 is a top plan view of the latch mechanism; and Fig. 9 is a sectional view on the line 9—9 of Fig. 7.

45 Describing my invention as illustrated in the drawings and referring to the various parts by reference numerals, 10 designates the base section of the ventilator which is a cylindrical sheet metal pipe adapted to fit 50 on to the upper end of an air shaft. About

its outer periphery is an angle iron reinforcing ring 11. Four angle iron braces 12 which are riveted or otherwise secured to the inside of the section 10 project upwardly and inwardly toward the axis thereof and have 55 their upper ends 13 horizontally disposed and secured to the under side of the bearing plate 14. Two strap iron members 16 positioned at right angles to each other extend diametrically across the base section 10 with their outer ends riveted to the vertical flanges on the angle bars 12. The center portions 17 of the strap iron braces 16 are bent to lie in a horizontal plane and at their intersection are provided with aligned apertures 18.

The top bearing plate 14 which is circular in form is provided on its top peripheral edge with a ball race to receive balls 20. A supporting block 21 provided on its under side with a depending annular flange 22 fits 60 over the bearing plate 14 with a cooperating ball race formed at the junction of the flange and block 21 in which the balls 20 rotate to take both the horizontal and vertical thrust of the supporting block 21. Rigidly secured 65 in a central opening in the block 21 and extending down through a central opening in the plate 14 is a tubular member 24 the bottom end of which extends through the apertures 18 in the braces 16. A collar 25 secured 70 on the tubular member 24 immediately below the plate 14 prevents displacement of the supporting block 21.

Secured to the under side of the lower brace member 16 is a cupped bearing member 27 through which the tubular member 24 extends. Within the cup portion of the bearing member 27 and secured to the tubular member 24 is a circular bearing block 28 provided on its lower peripheral edge with 80 a ball race which engages balls 29 held in a cooperating ball race at the outer edge of the cup portion of the bearing member 27.

The hood-like rotary cowl 30 of the ventilator is of common design, the same being 85 open at bottom and front, as shown at 31 and 32, respectively, and a top wall 34 slopes downwardly from the open front to the back. An angle iron ring 35 is secured about the bottom of the cowl to reinforce the same.

With its bottom edge telescoping over the top of the base 10 the cowl 30 is supported from the supporting block 21 by two diametrically arranged angle iron braces 37 which extend between opposite sides of the cowl. The supporting block 21 is provided with integral brackets 38 to which the upper brace 37 is secured and brackets 38^a to which the lower brace 37 is secured. A weight 39 is secured to the back of the cowl to provide a counterbalance for the weight of the structure at the opposite side of the pivot.

10 A series of louvers 40 one above another pivoted at their ends to the side walls of the cowl are arranged to close the front 32. The pivotal axis of each louver is near its top edge so that the louver falls by gravity to its closed position.

15 The louvers which are made of sheet metal are stamped to provide longitudinal ribs on 20 one side and corresponding grooves on the other, each louver having one rib 41 on its outer surface extending along its pivotal axis and one rib 42 near its bottom edge. The 25 top edge 43 of each louver is bent outwardly so as to fit into the groove 42 in the louver next above it when they are in the closed position so that they overlap and interlock to effectively close the front of the cowl.

30 The hinges for pivoting the louvers to the side walls of the cowl include two small metal strap members 45 each bent to provide a semi-cylindrical groove across its longitudinal center so that when the two similarly stamped 35 pieces are secured face to face and riveted or otherwise secured to the louver with the rib of one member positioned in the groove at 41 in the louver a cylindrical bearing is formed. A pin 47 extends through each cylindrical bearing and the adjacent side wall 40 of the cowl on which pin the louvers pivot.

35 The front edges of the louvers are pivotally connected to a strap 48 so that they are all 45 swung in unison by means of an operating rod 49 which has one end pivotally connected to the louvers and which operates through a suitable latch mechanism designated generally by the reference numeral 50.

40 The latch mechanism 50 comprises two vertically arranged parallel plates 52 provided with laterally bent edges 53 by which they are bolted to the cross braces 37 with the bottom edge of each plate resting on the supporting block 21. At two points the plates are 45 stamped to provide laterally projecting lugs 54 for spacing the plates apart, at which points the plates are secured together by rivets or other securing means. Journaled between the plates 52 with its edge directly 50 above the bore of the tubular member 24 is a sheave 55. The operating rod 49 is slidably received between the plates 52 and at its free end is bent to form a U-shaped portion 56 in which a second sheave 57 is journaled. 55 A flexible member 58 passes through the tubu-

lar member 24 over the sheave 55 about the sheave 57 and has its end secured to a pin 59 in the plates 52. By this flexible member the rod 49 is raised to open the louvers to which it is attached. On releasing the flexible member the louvers close by gravity.

70 For holding the louvers in various adjusted positions I provide notches 60 and 61 on that portion of the arm which slides between the plates 52. The notches 60 extending from the bottom edge of the bar are inclined toward its upper end, while the notches 61 cut in the upper edge of the bar are inclined toward its lower end, opening downward. The notches 60 and 61 are arranged in sets, the top and bottom notch of each set extending in approximately the same plane, in the particular form of latch illustrated. The plates 52 are provided with two sets of slots 64 and 65 in which pins 66 and 67 which extend between the two plates may move and between which pins the rod 49 is movable longitudinally. The upper slots 64 extend substantially at right angles from the rod 49 while the lower slots 65 are inclined slightly from the vertical toward the upper end of the bar 49. The slots 64 and 65 are so arranged that the rod 49 normally rides on the pin 67 in the bottom of the slot 65 and the pin 66 as it rests in the bottom of the slot 64 is slightly above the rod 95

90 In operation by pulling the flexible member 58 the rod 49 is moved longitudinally over the pin 67 until the first notch 60 engages the pin. Continuing to pull the member 58 the rod 49 is raised vertically by the pin sliding 100 in the slot 65 until the pin 66 which now rides on the upper edge of the rod drops into the notch 61. Releasing the tension on the member 58 the rod 49 drops back slightly as the pin 66 engages the bottom of the notch 105 61 and the pin 65 drops from the notch 60 to the bottom of the slot 65 as illustrated in full lines in Fig. 7. To open the louvers still further the rod 49 is moved upwards 110 by again pulling on the chain 58 until it is disengaged from the pin 66 and falls onto the pin 67. By continuing to pull the chain the rod 49 is moved longitudinally until the second notch 60 engages the pin 67, when 115 the rod is again lifted against the pin 66 which subsequently drops into the second notch 61. Releasing the flexible member 58 the rod 49 slips onto the pin 66 and the pin 67 again drops to the bottom of the slot 65.

To close the louvers the chain 58 is pulled 120 far enough to disengage the pin 66 from the notch 61 and the rod drops onto the pin 67 and moves longitudinally downwardly by gravity.

125 It is apparent that the latch and operating rod herein disclosed, while particularly suitable for retaining the louvers of a ventilator in open position is susceptible of use in other connections where the requirements are analogous.

Having thus described my invention, what I claim is:

1. In a ventilator of the class described having an outlet opening, a plurality of louvers pivoted thereto and to each other to swing in unison for closing said outlet, an operating bar secured to said louvers, a latch mechanism for holding said bar in adjusted position comprising a support in operative relation to which said bar is longitudinally movable, a holding member secured to said support and movable relative thereto and toward and from said bar, cooperating means on said bar for engaging said holding member, a shifting member movably secured to said support, means on said bar for engaging said shifting member, means on said support against which said shifting member operates causing it to move said bar toward said holding member as the bar is moved longitudinally, and means for moving said bar longitudinally relative to said support.

2. A catch mechanism for holding a bar member in longitudinally adjusted positions comprising a support in operative relation to which said bar is longitudinally movable, a holding member secured to said support and movable relative thereto and toward and from said bar, cooperating means on said bar for engaging said holding member, a shifting member movably secured to said support, means on said bar for engaging said shifting member, means on said support against which said shifting member operates causing it to move said bar toward said holding member as the bar is moved longitudinally, and means for moving said bar longitudinally relative to said support.

3. A catch mechanism for holding a bar member in longitudinally adjusted positions comprising a support in operative relation to which said bar is longitudinally movable, a holding member secured to said support and slidable relative thereto in a direction toward and from said bar, cooperating means on said bar for engaging said holding member, a shifting member movably secured to said support, means on said bar for engaging said shifting member, means on said support against which said shifting member operates causing it to move said bar toward said holding member as the bar is moved longitudinally, and means for moving said bar longitudinally relative to said support.

4. A catch mechanism for holding a bar member in longitudinally adjusted positions comprising a support in operative relation to which said bar is longitudinally movable, a holding member secured to said support and slidable relative thereto in a direction toward and from said bar, cooperating means on said bar for engaging said holding member, a shifting member slidably secured to said support, means on said bar for engaging said shifting member, means on said support

against which said shifting member slides causing it to move said bar toward said holding member as the bar is moved longitudinally, and means for moving said bar longitudinally relative to said support.

5. A catch mechanism for holding a bar member in longitudinally adjusted positions comprising a support in operative relation to which said bar is longitudinally movable, a guideway in said support, a holding member received in said guideway for moving toward and from said bar, cooperating means on said bar for engaging said holding member, a second guideway in said support on the opposite side of said bar, a shifting member received in said second guideway, means on said bar for engaging said shifting member to move it in said second guideway as the bar moves longitudinally, said shifting member, as it moves in the guideway, causing the bar to move against said holding means and be engaged thereby, and means for moving the bar longitudinally relative to said support.

6. A catch mechanism for holding a bar member in longitudinally adjusted positions comprising a support in operative relation to which said bar is longitudinally movable, a guideway in said support, a holding member received in said guideway for movement toward and from said bar, the movement toward said bar being caused by gravity, cooperating means on said bar for engaging the said holding member, a second guideway in said support on the opposite side of said bar, a shifting member received in said second guideway, means on said bar for engaging said shifting member to move it in said second guideway against gravity as the bar moves longitudinally, said shifting member, as it moves in the guideway, causing the bar to move against said holding means and be engaged thereby, and means for moving the bar longitudinally relative to said support.

7. A catch mechanism for holding a bar member in longitudinally adjusted positions comprising a support in operative relation to which the bar member is longitudinally movable, said support having a guideway, a pin movable in said guideway toward and from said bar, hook means on said bar adapted to engage on said pin when moved thereagainst in one direction, a second guideway in said support, a pin movable in said guideway on the opposite side of said bar, lugs on said bar for engaging said last mentioned pin to move it in said guideway when the bar is moved longitudinally, said pin as it moves in said guideway with said bar causing said bar to move toward the first mentioned pin to be engaged thereby, the lugs on said bar when the hook members on said bar are engaged by the first pin being moved out of contact with said second mentioned pin whereby it moves away from said bar,

and means for moving the bar longitudinally relative to the support.

8. A catch mechanism for holding a bar in longitudinally adjusted positions comprising spaced plate members between which the bar is longitudinally movable, a pair of slots in said plates, a pin secured in said slots for movement therealong, said slot being inclined toward said bar, lugs on said bar for engaging said pin to move it in said slots whereby said bar is shifted laterally, a holding member secured between said plates and movable toward and from said bar, hooked portions on said bar for engaging said holding means when said bar is shifted laterally by said pin, said pin, when the bar is engaged on said holding means, being moved to its normal position, and means for moving the bar longitudinally between said plates.

20. A catch mechanism for holding a bar member in longitudinally adjusted positions comprising spaced plates secured together between which said bar moves, said plates being provided with a pair of upwardly extending slots, a bar holding pin secured for movement in said slots, downwardly opening notches in the upper edge of said bar for securely engaging said pin, said plates having a second pair of slots inclined from the vertical in the direction of longitudinal movement of said bar, a shifting pin secured in said slots and normally resting in the bottom thereof on which the bar rides when moved longitudinally, abutments on the lower edge of said bar for engaging the shifting pin whereby as the bar is moved longitudinally the pin is moved in its slots lifting the bar against the holding pin, said abutments, when the bar is engaged on said holding pin, being moved out of engagement with said shifting pin, and means for moving said bar longitudinally between said plates.

10. A catch mechanism for holding a bar member in longitudinally adjusted positions comprising spaced plates secured together between which said bar moves, said plates being provided with a pair of upwardly extending slots, a bar holding pin secured for movement in said slots, downwardly opening notches in the upper edge of said bar for securely engaging said pin, said plates having a second pair of slots inclined from the vertical in the direction of longitudinal movement of said bar, a shifting pin secured in said slots and normally resting in the bottom thereof on which the bar rides when moved longitudinally, abutments on lower edge of said bar for engaging the shifting pin whereby, as the bar is moved longitudinally, the pin is moved in its slots lifting the bar against the holding pin, said abutments, when the bar is engaged on said holding pin, being moved out of engagement with said shifting pin, a sheave journaled between said plates, a flexible member passing over

said sheave and secured to said bar for moving said bar longitudinally while permitting limited lateral movement thereof.

In testimony whereof, I hereunto affix my signature.

JAMES H. McDERMINT.
